(57) **CLAIM**

The ornamental design for a modular enclosure, as shown and described.

DESCRIPTION

FIG. 1 is a first front perspective view of a modular enclosure according to an embodiment of the present design.

FIG. 2 is a first rear perspective view of the modular enclosure of FIG. 1.

FIG. 3 is a second front perspective view of the modular enclosure of FIG. 1.

FIG. 4 is a second rear perspective view of the modular enclosure of FIG. 1.

FIG. 5 is a front elevation view of the modular enclosure of FIG. 1.

FIG. 6 is a right side elevation view of the modular enclosure of FIG. 1.

FIG. 7 is a left side elevation view of the modular enclosure of FIG. 1.

FIG. 8 is a top plan view of the modular enclosure of FIG. 1; and,

FIG. 9 is a bottom plan view, without the mounted feet, of the modular enclosure of FIG. 1.

The dashed lines shown in FIGS. 1 through 9 illustrate the mounted feet, ear components, and threaded bores of the modular enclosure, which form no part of the claimed design. The broken away lines in FIGS. 1-5 and 8-9 indicate that no particular length is claimed.
